[57] CLAIM

The ornamental design for a retractable measuring tape with finger guard, substantially as shown.

DESCRIPTION

FIG. 1 is a top and left, front perspective view of a retractable measuring tape with finger guard showing my new design;

FIG. 2 is a left side elevational view thereof, the right side being substantially a mirror image thereto;

FIG. 3 is a front elevational view thereof;

FIG. 4 is a bottom plan view thereof; and

FIG. 5 is a rear elevational view thereof.
